UNITED STATES PATENT OFFICE.

LÉON TIRIFAHY, OF CHARLEROI, BELGIUM.

EXPANDED SHEET METAL.

Application filed April 11, 1927, Serial No. 182,891, and in Belgium April 20, 1926.

The present invention relates to the manufacture of expanded metal and it has for its object to provide slit and ribbed metal sheets that will be particularly adapted for 5 use in armed concrete structures.

In particular the invention has reference to metal sheets in which parallel series of H-shaped slits are cut prior to their expansion. When expanded such sheets comprise 10 parallel bands of metal connected at intervals by oblique ties or strands which, in the course of expansion, take up an inclined position wth respect to the general plane of the sheet and finally stand on edge in the fully 15 expanded sheet.

While this more or less inclined position of the ties has been considered favorable in so far as it stiffens the metal it has been observed that very wide meshes are thus 20 formed through which cement is allowed to pass too freely so that its adherence to the ties is impaired and the use of the cement gun is precluded.

An object of the present invention is to 25 provide a form of expanded metal in which the ties are prevented from taking up an inclined position so that, for a given degree of expansion, much narrower openings are formed, the portions of metal connecting 30 adjacent ties being pressed into the shape of hooks whereby a particularly efficient binding of the cement is secured.

A further object of my invention is to 35 provide expanded metal provided with longitudinal ribs, wherein not only the flat sections between the ribs, but the ribs themselves may be slit and expanded, thus not only affording the desired stiffness but providing a far better adherence of the concrete to the ribs than is obtainable with the 40 usual plain ribs.

The accompanying drawings illustrate 45 several examples of realization of the present invention.

Figs. 1, 2, 3 and 4 show various arrangements of the H-shaped slits in the metal sheets prior to their expansion and Figs. 5, 6, 7 and 8 respectively are corresponding views of the expanded sheets.

Figs. 9 and 10 show in plan and end view 50 respectively an expanded sheet having ribs with transverse projections.

Figs. 11 and 12 likewise show an expanded sheet provided with slit and expanded ribs.

In Figs. 1 to 4, the H-shaped slits are 55 denoted *a*. In Fig. 1 they alternate with sin-

gle longitudinal slits *b* arranged axially of the H-shaped slits but separated therefrom at both ends by a portion of unslit metal *c*. When the sheet metal is expanded (Fig. 5) 60 these portions *c* can be bent at right angles to the plane of the sheet so as to form hook-shaped projections adapted to project into the concrete. Or in the course of expansion the binding portions *d* can be raised obliquely, their ends *c* then being bent down in a direction parallel to the sheet. 65

As shown in Fig. 5 this form is very simple and forms a very strong lathing all the parts of which have strong connections 70 between them. It can conveniently be made from sheets of basic steel which withstand very well the stresses exerted thereon in the course of the expansion of the metal as also of the handling and use thereof. 75

In the form according to Figs. 2 and 6 instead of each slit *b* I have provided two slits *d*, while in Figs. 3 and 7 the H-shaped slits *a* alternate with straight slits *e* no longer in the longitudinal but in the lateral direction. 80 Finally Figs. 4 and 8 show the results obtained with two series of H-shaped slits *a* and *a'*, the latter being slightly offset with respect to the former. These various forms and others which might be obtained with 85 different arrangements of the slits, make it possible to multiply the hooks or projections for engaging the concrete. In practice however the form illustrated in Figs. 1 and 5 is suitable for most cases; it answers best the 90 requirements as regards simplicity and strength and permits of using particularly strong machinery, thus lowering the cost of manufacture.

As stated above the slits may be distributed over longitudinal zones or bands separated by bands of plain metal which may be pressed so as to form ribs. These may be plain as in some known forms of expanded metal, but it is advantageous to provide 100 them with projections either by pressing or by slitting or otherwise.

Figs. 9 and 10 show ribs *f* provided at intervals with transverse projections or ridges *g* made by pressing in the course of 105 the production of the rib, either in a press or in a rolling mill, the dies of the press or the rolls of the rolling mill then being provided with suitable projections and grooves. In forming these ridges the metal may be 110 stretched, so that the length of the ribs is not altered. In use these ridges efficiently

prevent any longitudinal slipping of the armature within the concrete.

In the example of Figs. 11 and 12, the metal bands from which the ribs are formed are cut so as to form slits *h* similar to those of the flat portions. The openings thus made in the expanded metal permit of the concrete engaging into the ribs and give a perfect adherence, making any slipping impossible within the structure. This form of rib moreover allows of a greater expansion of the metal sheet and increases the moment of inertia of the ribbed sheet. Hooks *c'* similar to the hooks *c* can be formed by bending the metal of the ribs.

The metal sheets according to the invention are preferably manufactured in two stages, first the cutting of the slits in a press that also raises the metal portions which are to form the hooks, and then the expansion in an expanding machine which may be a press or a rolling mill. In the case of ribbed sheets the expansion may advantageously be carried out in a rolling mill in which the successive pairs of rolls have grooves of increasing depth so as to gradually form ribs of the required height while at the same time exerting on the slit portions the amount of stretching required to expand the metal.

By reason of the shape and arrangement of the slits made in accordance with the present invention the strains exerted on the metal in the course of the expansion are reduced to the minimum and sudden stresses can be avoided, which makes it possible to use sheet metal made of basic steel. Indeed as the longitudinal portions of each H-shaped slit extend on either side of its transverse portion, the expansion proceeds from both sides of said transverse portion and extends on twice the length available with the slits in the known types of expanded metal so that in comparison therewith the sheets according to the invention require less power to realize a given degree of expansion. As they also have a greater number of binding portions they moreover possess a greater strength per unit weight for a given degree of expansion. It will

further be noticed that the openings produced by the expansion of the H-shaped slits are not of excessive width owing to the fact that they are partly filled by the projections *c* facing each other, so that the concrete can easily be applied on the metal by means of the cement gun. The manufacture of these sheets is also more easy and more economical as the great length of the slits makes it possible to use stronger cutting tools and to increase the speed of the progress of the sheets through the slitting machines.

It will be understood that the shapes of expanded metal and ribs described and shown in the accompanying drawings are simply given by way of example and that they may be varied or combined in various ways without departing from the scope of the invention.

I claim:

1. A sheet of expanded metal having H-shaped openings formed therein and arranged in parallel relation, said sheets comprising parallel longitudinal bands of entire metal, pairs of oblique ties connecting said bands with each other; said ties extending with their full width substantially in the same plane as said longitudinal bands, and hook-shaped portions of metal connected to each of said pairs of ties.

2. A sheet of expanded metal comprising parallel longitudinal ribs and flat sections comprised between said ribs, the metal forming both said sections and said ribs having H-shaped openings formed therein and arranged in parallel relation, said sections and said ribs comprising each parallel longitudinal bands of metal, pairs of oblique ties connecting said bands with each other, the ties in the flat sections extending with their full width substantially in the same plane as the adjacent longitudinal bands, the ties in said ribs extending with their full width substantially in the same plane as the adjoining edges of adjacent longitudinal bands, and hook-shaped portions of metal connected to each of said pairs of ties.

In testimony whereof I affix my signature.

LÉON TIRIFAHY.
